US00D991186S

(12) **United States Design Patent** (10) Patent No.: **US D991,186 S**
Underhill et al. (45) Date of Patent: ** Jul. 4, 2023

(54) **BATTERY CABLE ASSEMBLY**(71) Applicant: **THE NOCO COMPANY**, Glenwillow, OH (US)(72) Inventors: **Derek Michael Underhill**, Tempe, AZ (US); **Jonathan Lewis Nook**, Gates Mills, OH (US)(73) Assignee: **THE NOCO COMPANY**, Glenwillow, OH (US)(**) Term: **15 Years**(21) Appl. No.: **29/763,130**(22) Filed: **Dec. 21, 2020****Related U.S. Application Data**

(63) Continuation-in-part of application No. 29/761,829, filed on Dec. 11, 2020.

(51) **LOC (14) Cl.** ..... **13-03**(52) **U.S. Cl.**USPC ..... **D13/149**; D13/120; D13/133; D13/148(58) **Field of Classification Search**

USPC D13/107, 118-120, 121, 127, 133, 137.4, D13/148, 149, 153, 160-161, 178; D14/205, 218

CPC H02J 7/0063; H01H 85/32; H01H 85/201; H01H 85/2035

CLAIM

The ornamental design for a battery cable assembly, as shown and described.

DESCRIPTION

FIG. 1 is a perspective view of a new design for a battery cable assembly;

FIG. 2 is a top plan view of FIG. 1;
FIG. 3 is an enlarged perspective view of a new design for a battery cable assembly, showing battery clamps connecting to the battery cable assembly;
FIG. 4 is an enlarged perspective view of a connector end of a battery cable assembly;
FIG. 5 is an enlarged perspective end view of a connector end of a battery cable assembly;
FIG. 6 is an enlarged top plan view of a connector end of a battery cable assembly;
FIG. 7 is an enlarged bottom plan view of a connector end of a battery cable assembly;
FIG. 8 is an enlarged left side elevation view of a connector end of a battery cable assembly;
FIG. 9 is an enlarged right side elevation view of a connector end of a battery cable assembly;
FIG. 10 is an enlarged end view of a connector end of a battery cable assembly;
FIG. 11 is an enlarged opposite end view of a connector end of a battery cable assembly;
FIG. 12 is an enlarged perspective view of an assembled fuse holder of a battery cable assembly;
FIG. 13 is an enlarged perspective view of a partially assembled fuse holder of a battery cable assembly;
FIG. 14 is an enlarged perspective view of the opposite side of FIG. 13;
FIG. 15 is an enlarged perspective view of a disassembled fuse holder of a battery cable assembly; and,
FIG. 16 is a side elevation view of FIG. 15.
The broken line portion of the drawings is included to show portions of the battery cable assembly the form no part of the claimed design.
